Primary Examiner — Kendra Leslie Hamilton

(57) **CLAIM**

The ornamental design for a veterinarian collar for pet, as shown and described.

DESCRIPTION

FIG. 1 is a top perspective view of the veterinarian collar for pet, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the veterinarian collar for pet of FIG. 1, shown exploded for clarity of disclosure; and, FIG. 10 is a top perspective view of the veterinarian collar for pet of FIG. 1, shown in a condition of use.

In the drawings, the broken lines on the veterinarian collar for pet depict portions of the veterinarian collar for pet that form no part of the claimed design. The broken lines showing a pet in FIG. 10 depict environment structure that forms no part of the claimed design. All broken lines form no part of the claim.

1 Claim, 10 Drawing Sheets
